UNITED STATES PATENT OFFICE

96,032

DESIGN FOR A TEXTILE FABRIC OR SIMILAR ARTICLE OF MANUFACTURE

John F. Gaul, Jr., Clifton, N. J., assignor to Botany Worsted Mills, Passaic, N. J., a corporation of New Jersey

Application May 13, 1935, Serial No. 56,809

Term of patent 14 years

To all whom it may concern:

Be it known that I, John F. Gaul, Jr., a citizen of the United States of America, residing at No.
1110 Van Houten Avenue, in the town of Clifton,
State of New Jersey, have invented a new, original,
and ornamental Design for a Textile Fabric or Similar Article of Manufacture, of which the following is a specification, reference being had to the accompanying drawing, forming a part thereof. Fig. 1 of the drawing is a face view of a piece of textile fabric embodying my design. Fig. 2 shows a section thereof taken along the line 2—2

of Fig. 1, while Fig. 3 shows a section thereof taken along the line 3—3 of Fig. 1, Figs. 2 and 3 showing the difference in levels of the several areas.

I claim:

The ornamental design for a textile fabric or similar article of manufacture substantially as shown and described.

JOHN F. GAUL, JR.
